[57] CLAIM

The ornamental design for a wheel cover exterior surface for a personnel carrying vehicle, as shown and described.

DESCRIPTION

FIG. 1 is a perspective view of the wheel for a personnel carrying vehicle showing our new design;

FIG. 2 is a front elevational view thereof;

FIG. 3 is a section view taken along lines 3—3 of FIG. 2;

FIG. 4 is an enlarged detailed view of the circled section labeled 4 shown in FIG. 3; and,

FIG. 5 is a rear elevational view of the wheel of FIG. 1.
